FEEDING MEANS

Charles N. Ash, Chicago, Ill., assignor to Edward C. Chandler, Cleveland, Ohio

Application May 13, 1935, Serial No. 21,131

4 Claims. (Cl. 141—9)

This invention relates to means for feeding a solution of chemicals to a machine for washing dishes or the like and using washing and rinsing water from different sources in its operation.

5 The object of the invention is to provide means for automatically maintaining a given strength of washing solution by delivering detergent chemicals to the machine proportionally dependent upon delivery of water to the machine from 10 either source.

The exact nature of the invention together with further objects and advantages thereof will be apparent from the following description taken in connection with the accompanying drawing, 15 in which Fig. 1 is a conventionalized elevation partly in section, showing the essential parts of a typical washing machine with my invention applied thereto; Fig. 2 is an enlarged sectional detail of parts appearing in Fig. 1.

20 With reference now to the drawing, 1 represents generally the housing of a dish-washing machine having an elevated open top container 2 for the washing solution, rack means 3 there- 25 above for supporting the dishes 4 to be washed, and screening 5 disposed between the dishes and the container to catch solids removed from the dishes in the washing operation. A hot water supply line 6 is arranged for delivery of washing water to the container 2 subject to manipulation 30 of the valve 7 by the operator. An overflow line 8 leads from the container to maintain a liquid level therein and provide removal of floating particles, and a drain 9 is provided for the container, by which heavier solids may be removed.

35 The washing of the dishes is accomplished by jets from the nozzles of a spray device 10, directing upon the dishes, liquid recirculated from the container 2. For the purpose a pump 11 driven by motor 12, receives liquid from the 40 container by way of the pipe 13 and delivers to the spray device by way of a pipe 14.

For rinsing of the dishes, a rinse spray device 15 supplied by hot water from the line 16 subject to valve 17, is arranged above the dishes to rain 45 rinse water down thereupon, this water draining into the container 2. For simplicity the valve 17 is shown as for manipulation by the operator, but such valve may be arranged for automatic operation dependent upon completion of the 50 washing operation, the advanced position of the dish-containing rack 3, etc., as will be appreciated by one familiar with the art.

The supply lines 6 and 16 are separate, that 55 the rinse line 16 may deliver water of a higher

temperature than is necessary for the washing water.

Mounted upon the top of the housing 1 of the washing machine, is a feeding device 18 for detergent chemicals, having a removable cover 5 19 by which chemicals in crystalline or other suitable form may be introduced, a water inlet 20, and an outlet pipe 21 leading to the container 2 of the washing machine. Details of the feeding device are not material here, it being sufficient to state that the device receives water from its inlet 20, dissolves chemicals in this water during flow of the latter through the device, and delivers the resultant solution of these chemicals through the pipe 21 in proportion to water 10 received at the inlet 20. This inlet includes a needle valve 20a and a sight glass 20b by which the small amount of water receivable by the feeding device may be accurately and easily adjusted by the operator.

20 What has thus far been described is not new in the art, as will be appreciated by one familiar therewith.

According to this invention, a water supply connection for the feeding device is had from both the water inlet lines 6 and 16 serving the 25 washing machine. For this purpose a T fitting 22 is piped as indicated at 23 and 24 to receive water from the pipes 16 and 6, responsive to opening of their valves 17 and 7 respectively; 30 that is, the connections 23 and 24 leading to the fitting 22 join the pipes 16 and 6 on the washing machine side of the valves 17 and 7. A pipe 25 leads from the fitting 22 to the inlet 20 of the feeding device 18.

35 That the fitting 22 may act as a two-way valve, to permit flow into the line 25 from either of the lines 23, 24, but prevent flow between the lines 23 and 24, a ball 26 is arranged within the fitting to move between the ends of the pipes 23 and 24, and seat upon either to close its mouth. Although other valve means might be employed for the purpose, that here shown is simple, inexpensive and otherwise satisfactory.

40 Operation will be as follows, assuming suitable chemicals within the feeding device 18, the lines 6 and 16 connected to sources of hot water supply. To start the machine it is first necessary that its container tank 2 be filled with water. This is accomplished by opening of the 45 valve 7 until water commences to overflow through the pipe 8. While the valve 7 is open, the pipe 6 will be filled with water under pressure so that this water will find its way through the pipe 24 to the fitting 22. This will move the 50

55

ball 26 from its full line position to its dotted line position, Fig. 2, so that flow into the pipe 23 is prevented, but takes place through the pipe 25 to the feeding device inlet 20. The valve of

5 the inlet device permits a predetermined amount of such water to flow through the device, dissolving chemicals in its progress and thereafter entering the container 2 by way of the pipe 21.

Thus as the container 2 receives water from 10 the pipe 6, it also receives in definite proportion to this water, a solution of chemicals from the feeding device 18, and the machine is ready to wash.

The rack 3 containing articles to be washed, 15 the motor 12 is started, actuating the pump 11, and throwing jets of the detergent-bearing washing water from the container 2 against the dishes, this water draining back into the container and being recirculated by the pump.

20 After completion of the washing part of the cycle, the pump is stopped or the washed articles otherwise removed from the effect of the washing jets. The valve 17 is thereupon opened, admitting rinse water through the pipe 16 and 25 rinse nozzles 15. Thus the washed articles are rinsed, the rinse water ultimately falling into the container 2 and causing the latter to overflow through the pipe 8. Obviously the contents of the container are greatly diluted by 30 this rinse water. However, according to this invention, when the valve 17 is opened, some of the rinse water finds its way to the fitting 22 through the pipe 23, moving the valve 26 to its full line position, Fig. 2, and flowing through the 35 pipe 25 to the inlet 20 of the feeding device, as indicated by the arrows in Fig. 2. As water enters the feeding device, delivery of washing solution takes place as before, through the pipe 21 to the container 2, in amounts proportional 40 to the amount of rinse water. Upon closing of the rinse valve 17, delivery of chemical solution terminates coincidentally with delivery of rinse water.

Thus whatever amount of water is delivered 45 to the washing machine, whether it be washing water or rinse water, a proportional amount of chemical solution is simultaneously delivered to the container, so that the washing strength of the latter is maintained. This strength is determined by the setting of the inlet valve 20a 50 of the chemical feeding device, and as already stated, is independent of the valves 7 and 17.

What I claim is:

1. In combination with a washing machine 55 having washing and rinsing means and valved lines for separate supply of washing water and rinse water thereto, a chemical feeding device having a chemical container with a solvent water inlet thereto and an outlet connection for 60 solvent solution leading therefrom to the washing means of said machine, means providing connections from both said water supply lines to said feeding device inlet for feeding of water to the latter and feeding of solution from the

feeding device to said washing means during feeding of water to said machine from either of said lines and including a single connection to said feeding device and means for preventing flow between said supply lines.

2. In combination with a washing machine having washing and rinsing means and valved lines for separate supply of washing water and rinse water, a chemical feeding device having a chemical container with a solvent water inlet thereto and an outlet connection for solution leading therefrom to the washing means of said machine, means providing connections from said water supply lines, on the washing machine side of their valves, to said feeding device inlet for feeding of water to the latter and feeding of solution from the feeding device to said washing means automatically proportional to feeding of water to said machine from either of said lines, said means including check valve means arranged to prevent flow to either supply line from the other.

3. In combination with a washing machine having washing and rinsing means and valved lines for separate supply of washing water and rinse water, a chemical feeding device having a chemical container with a solvent water inlet thereto and an outlet connection for solution leading therefrom to the washing means of said machine, means providing connections from said water supply lines, on the washing machine side of their valves, to said feeding device inlet for feeding of water to the latter and feeding of solution from the feeding device to said washing means automatically proportional to feeding of water to said machine from either of said lines, said means including a two-way check valve located in said connections to be effective to permit flow from either water supply line to said feeding device but to prevent flow from either supply line to the other.

4. In combination with a washing machine having means for supporting the articles to be washed and a container for washing solution arranged to receive drainage from said articles, means for circulating said solution over said articles, means for rinsing said articles, means providing for overflow from said container, said washing machine having valved lines for supply of washing water to said container and rinse water to said rinse means, a chemical feeding device having a chemical container with a solvent water inlet thereto and an outlet connection for solution leading therefrom to said container, and connections from said water supply lines, on the washing machine side of their valves, to said feeding device inlet for feeding of water to the latter and feeding of chemical solution from said feeding device to said container automatically proportional to feeding of water to said machine from either of said lines, said connections including check valve means arranged to prevent flow from either water supply line to the other.

CHARLES N. ASH.
